UNITED STATES PATENT OFFICE.

EDWARD C. SOUNNEY AND THOMAS D. SOUNNEY, OF SACRAMENTO, CALIFORNIA.

INVALID-BED.

SPECIFICATION forming part of Letters Patent No. 552,672, dated January 7, 1896.

Application filed October 16, 1895. Serial No. 565,899. (No model.)

To all whom it may concern:

Be it known that we, EDWARD CHARLES SOUNNEY and THOMAS DAVID SOUNNEY, citizens of the United States, residing at Sacramento, county of Sacramento, State of California, have invented an Improvement in Invalids' Beds; and we hereby declare the following to be a full, clear, and exact description of the same.

10 Our invention relates to the class of beds for invalids; and it consists in the novel invertible rotatable frame, the supports therefor, the mattress or mattresses, and the novel detachable and adjustable connections between the mattresses and the frame, all of which we shall hereinafter fully describe.

15 The object of our invention is to provide a bed in which a perfectly helpless patient may be turned from his back to his face, and vice versa, and the mattress on which he had been lying removed upon the substitution of another mattress to receive him in his changed position, thus not only relieving the invalid by a change of position but affording opportunity to change and freshen the bed.

20 Referring to the accompanying drawings, Figure 1 is a perspective view of our bed, the second mattress L being shown about to be placed in position. Fig. 2 is an end view from the inside showing the means for fastening and adjusting the side rails. Fig. 3 is a similar view from the outside showing the steady-ing-legs. Fig. 4 is an elevation of the hanger-screws. Fig. 5 is a detail of the releasing-levers. Fig. 6 is a detail of the connection for board M.

25 A are circular ends of the bed-frame. These rest and are turnable upon rollers b in brackets B on the floor.

30 C are the side rails or bars, two on each side, one above and one below. They are connected with the circular ends in suitable manner; but the best connection is an adjustable one, in order to vary their separation to suit different patients. The adjustable connection here shown consists of a slotted plate a in the ends, and into which the ends of the side rails are fitted and are held at the required distance apart by means of the piv-

35 oted or swinging ratchet-bars a', which engage them.

40 In order to hold the turnable frame steady upon its supporting-rollers, there is attached to each side of one end A a leg D, which is a peculiarly adjustable one, in order to adapt 55 it to move out of the way to permit the bed to rotate and to fall again to position for use.

45 The upper end d of the leg is bent inwardly and an elongated slot d' is made in the upper portion of said leg and extends also into the bent end d. A pin or stud a² on the end of a cross-piece a³ on the circular end A normally fits in the extremity of the slot d' in the bent end, and thus the leg is held and serves as a support; but upon moving the leg inwardly so that it slips its slot along the pin or stud a² to its bend the circular end can then 55 rotate, as its pin or stud will travel down the length of the slot d' nearly to its bottom, and then, upon reaching the uprising side of its 60 rotation, the pin or stud will travel up again in the slot and will reach its upper extremity 65 and carry the leg up with it to a stable position on the other side, in which it will again 70 serve as a support. During this movement 75 the opposite leg has been simply bodily carried up and over by the turning end A, as it only requires that the leg on the side toward 80 which the turn is made shall be disposed of to permit the turn to be made.

75 E is a mattress, and F is the frame to which it is attached. At one end the frame has small wheels G, upon which it can be rolled in order to transfer it easily from place to place.

80 Let into or formed with the side bars of the mattress-frame is a vertically-disposed socket or sleeve H, there being four of these, one at or near each end of each side bar. The lower end of each socket or sleeve is formed or provided with a ratchet-clutch h, and around it just above the clutch is a series of radially-projecting pins h'.

85 In each socket or sleeve is fitted the shank i of a suspending or hanger screw I. This 90 screw is formed of two spirally-directed bars, the course of which is similar to that of a duplex thread. The separation between them

is sufficient to permit the passage of a bar having the diameter of the side rails C of the bed-frame, and one of said spiral bars is made longer than the other, for a purpose we shall 5 presently describe.

Supported upon a nut i' on the lower end of the screw-shank i is a ratchet-clutch i², adapted to engage the clutch h, and when so engaged to prevent the hanger-screw I from 10 turning. The clutch i² is recessed on its upper surface, and in the cavity thus formed lies the head j of the lever J, which extends outwardly through a groove i³ in the side of the clutch. Lying in this same cavity is the 15 head k of a second lever K, which is so bent as to be able to fulcrum on lever J, and thereby to lift its head when said lever is pressed down upon. Both lever-heads slide freely upon shank i, and normally lie well within 20 the cavity or recess of clutch i², so that they do not interfere with the engagement of said clutch with clutch h; but when said levers are pressed together, the heads separating and bearing in opposite directions against 25 the clutches separate them and break their engagement.

L is a second mattress having a frame with wheels and sockets or sleeves and hanger-screws and attached parts precisely like those 30 of mattress E. This mattress L, being intended to support the patient upon his face, is shaped, as shown, to give him the comfort of disposing of his arms about the neck l, supporting his shoulders on the wide portion 35 l' and his face on the head-piece l².

M is a board, which by means of a bracket m, to which it is secured, and an adjustable clamp m' is secured to the side rails C in a position to act as a stop for the patient when being turned with the bed.

The operation of the bed is as follows: Let it be supposed that it is yet without an occupant. One of the mattresses, say E, is then rolled along on the wheeled end of its frame 45 until it is alongside of the bed-frame, whereupon it is set on its side edge. Then one end is raised until the hanger-screw at the side of said end is in position to hook the longer end of one of its screw-bars over the side rail 50 C. Then the other end is lifted and its hanger-screw is hooked over the same side rail. Then the mattress is laid over flatwise on top of the bed-frame and its hanger-screws on the other edge engage the opposite side 55 rail C. The hanger-screws being thus fitted and started rotate under the weight of the mattress and screw themselves down to their bases over the side rails. Now that leg D, which is on the side to which the bed is to be 60 turned, is manipulated, as heretofore described, in order to get it out of the way, and thereupon the whole bed is invertibly rotated through a half-turn on its rollers b. As soon as the mattress reaches its new and reversed 65 position, its weight causes the engagement

of the clutches h and i², and these prevent the hanger-screw from turning, and consequently they suspend the mattress from the lower side rails C. The patient is now placed in the bed. To change him the mattress L 70 is rolled into position and is adjusted to the top side rails C in the manner described in regard to mattress E and directly over the patient. The board M is now placed in position and the device rotated as before, the patient remaining between the two mattresses. 75

When mattress L is down and mattress E is up, the patient is lying on the former face down. Mattress E is now removed by a process the reverse of that by which it is applied. 80 When called into use again it is replaced and the patient turned with it and then mattress L is removed. To remove the patient readily the levers J and K on one side are pressed together and the clutches h and i² disengaged, 85 whereupon the hanger-screws rotate and allow that side of the mattress to come down to the floor. Then by relieving the bed-frame of its leg D said frame will turn by reason of the weight and thus allow the other side of 90 the mattress to come down to the floor. The object of the pins h' around clutch h is to provide by successive engagement with lever K, at the will of the operator, a check upon the turning of the hanger-screw and the descent of the mattress. 95

Having thus described our invention, what we claim as new, and desire to secure by Letters Patent, is—

1. In an invalid's bed, the combination, of 100 a frame having circular ends, means supporting said ends and adapting the frame to be invertibly rotatable, and independent, detachable mattresses to alternately support the patient.

2. In an invalid's bed, the combination of 105 a frame having circular ends, rollers upon which said ends are supported whereby the frame is invertibly rotatable, and independent, detachable mattresses adapted to alternately support the patient.

3. In an invalid's bed, the combination of 110 a frame having circular ends, rollers upon which the ends are supported whereby the frame is adapted to be invertibly rotated, legs 115 for holding the frame in position and independent, detachable mattresses adapted to alternately support the patient.

4. In an invalid's bed, the combination of 120 a frame having circular ends, rollers upon which the ends are supported whereby the frame is adapted to be invertibly rotated, legs for holding the frame in position, said legs having bent slots freely fitting over a pin or stud on the end of the frame whereby they 125 may be turned out of the way when the frame is turning, and independent, detachable mattresses adapted to alternately support the patient.

5. In an invalid's bed, the combination of 130

the ends having the slotted plates, the side rails fitting said plates and the pivoted ratchet bars for locking the side rails.

6. The combination, with a bed frame and a mattress frame, of a detachable connection between bed-frame and mattress frame, consisting of a duplex twisted bar, and means for holding and relieving said bar to keep it from or to permit it to axially rotate.

10 7. In an invalid's bed, the combination of a bed-frame having side rails, a mattress frame and the means for detachably connecting the side rails and the mattress frame consisting of the socket or sleeve on the mattress frame having the clutch, the hanger screw having the shank fitted in the socket or sleeve and the clutch on the shank engaging the clutch on the socket or sleeve.

15 8. In an invalid's bed, the combination of a bed-frame having side rails, a mattress frame and the means for detachably connecting the side rails and the mattress frame consisting of the socket or sleeve on the mattress frame having the clutch, the hanger screw having the shank fitted in the socket or sleeve, the clutch on the shank engaging the clutch on the socket or sleeve, and the levers for disengaging the clutches.

20 9. In an invalid's bed, the combination of a bed-frame having side rails, a mattress frame

and the means for detachably connecting the side rails and the mattress frame consisting of the socket or sleeve on the mattress frame having the clutch, the hanger screw having the shank fitted in the socket or sleeve, the clutch 35 on the shank engaging the clutch on the socket or sleeve, the levers for disengaging the clutches, and the pins for engaging one of the levers to hold it and check the turning of the hanger screw when required.

10 10. In an invalid's bed, the combination of a bed-frame having circular ends, means supporting said ends and adapting the frame to be invertibly rotated, independent detachable mattresses adapted to alternately support the 45 patient, and a board connected with the bed-frame for holding the patient in between the mattresses as the bed turns.

11. A mattress to receive a patient upon his face, composed of a body portion, a neck to receive the embrace of the arms, a wide portion to support the shoulders and a head-piece.

In witness whereof we have hereunto set our hands.
